UNITED STATES PATENT OFFICE.

HENRY A. OWEN, OF WHITINSVILLE, MASSACHUSETTS, ASSIGNOR, BY MESNE ASSIGNMENTS, TO DRAPER CORPORATION, OF HOPEDALE, MASSACHUSETTS, A CORPORATION OF MAINE.

FEEDER-ACTUATING MECHANISM FOR WEFT-REPLENISHING LOOMS.

1,291,101.

Specification of Letters Patent.

Patented Jan. 14, 1919.

Application filed April 22, 1915. Serial No. 23,050.

To all whom it may concern:

Be it known that I, HENRY A. OWEN, a citizen of the United States, residing at Whitinsville, in the county of Worcester, 5 State of Massachusetts, have invented a certain new and useful Improvement in Feeder-Actuating Mechanism for Weft-Replenishing Looms, of which the following is a specification, reference being had therein to the 10 accompanying drawings.

The invention has relation to weft-replenishing looms of the bobbin-changing class. More particularly, it has relation to the mechanisms or devices that are employed in 15 such looms for actuating the feeders thereof to present reserve filled bobbins or other loaded weft-carriers successively in position in readiness for transfer to the shuttle which is to be kept charged with weft or filling 20 and in working condition.

I eliminate the devices and connections heretofore customarily employed in practice for actuating a feeder from or under control of the transerrer, and provide, instead, a 25 train of actuating connections comprising a dog which engages the ratchet of the feeder, a cam on a rotating shaft of the loom, operating to move the dog to its starting position independently of the transerrer, and means 30 for operating the said dog to actuate the feeder to present the leading bobbin or other weft-carrier against the end-stop and hold it pressed against the said end-stop until the 35 transfer of such bobbin or weft-carrier. The invention includes, more specifically, novel features of construction embodied in the actuating devices of the dog. Also, means for manually controlling the dog. Also, improved means for disengaging the 40 dog and also the detent from the ratchet of the feeder so as to leave the latter free to be shifted backward and forward by the weaver.

Illustrative embodiments of the invention 45 are shown in the drawings, which represent in Figure 1, in side elevation, certain portions of a bobbin-changing weft-replenishing loom with one of the said embodiments combined therewith. Fig. 2 is a side elevation showing a different embodiment of the 50 features of the invention.

Referring to certain of the usual parts of a bobbin-changing weft-replenishing loom, so far as the same are shown in the 55 drawings, such parts comprise the loom-

frame 1, the cam-shaft 2, the lay-beam 3, the lay-sword 4, and a shuttle 5, the latter being represented as occupying the shuttle-box at the replenishing side of the loom and confined between the front-plate 6 of the 60 said shuttle-box and the binder 7 of the latter. Referring more particularly to the replenishing mechanism, 8 is the stand at the inner end of the feeder, 9 is the stud projecting outward from said stand and on 65 which the rotary parts of the feeder are sleeved, 10 is the notched disk at the inner end of the feeder which supports the heads of the bobbins or other weft-carriers α , α , 11 being the ratchet-wheel of the feeder, and 70 12 the detent or holding pawl pivoted at 13 upon a fixed support and normally swinging into engagement with the teeth of the said ratchet-wheel. 14 is the transerrer, 15 the fixed stud on which the transerrer 75 is mounted pivotally, and 16 the latch or dog of the transerrer. 17 is the bunter carried by the lay and which serves in the forward movement of the lay to engage with the said latch or dog 16 when the latter is 80 upraised through the action of the weft-detecting devices of the loom, so that the said bunter may transmit movement through the latch or dog to the transerrer, to actuate the transerrer to feed the leading bobbin 85 or other weft-carrier α from its position against the end-stop 18 into the shuttle 5, the latter being momentarily beneath the transerrer in position to receive the bobbin or other weft-carrier driven down from the 90 feeder by the action of the transerrer.

Referring now more particularly to the parts which are involved in the present invention, and first to the embodiment shown in Fig. 1, the actuating dog for the feeder 95 is shown at a , its upper end being arranged to engage with the teeth of the ratchet-wheel 11, and its lower end being connected by a pivot b with an actuating member, which herein is a lever c , the latter being 100 fulcrumed at c' upon a support in connection with the loom-frame, and the pivot b for the dog a being combined with the forward arm of the said lever. The said actuating member is, as hereinbefore indicated, arranged to be actuated in one direction by means of a tappet or cam upon a rotating shaft of the loom. In the drawings the rear arm of the lever c carries a trip-arm d which is connected pivotally to 110

it at d' , the said trip-arm being adapted to be engaged by the tappet or cam e fixed upon and rotating with the cam-shaft 2. The tappet or cam and trip-arm are arranged to co-5 operate so that through the engagement of the tappet or cam with the trip-arm the lever c and dog a are actuated to retract the dog to the starting position of the latter, thereby pulling it back a distance of one, two or 10 more teeth of the ratchet-wheel 11, as may be provided for, the return movement of the lever c which follows the said action of the cam being occasioned with yielding force so as to cause the dog to turn the feeder and 15 bring the next succeeding bobbin or weft-carrier yieldingly against the end-stop 18, and keep it pressed yieldingly against the latter. Such return movement is effected in the construction herein shown by means of 20 the contracting spiral spring f , which latter is engaged with the lever c . Other means of applying yielding force may be employed in practice. The dog a is represented as drawn toward the ratchet 11 by means of a 25 contracting spiral spring a' so as to keep its engaging end in contact with the teeth of the said ratchet-wheel, although ordinarily this spring may be omitted and the weight of the dog itself be depended upon to hold 30 the acting end of the dog in engagement with the ratchet. The extent of the swinging movement of the lever c in opposite directions is fixed by means of stops c^2 , c^3 , in 35 connection with the pivotal mounting of the lever c , such stops being disposed for engagement with the said lever at opposite sides of the fulcrum c' of the latter. Other stop arrangements may be substituted.

A characteristic feature of the trip-arm d 40 is the fact that it is mounted pivotally upon the actuating member or lever c by means of the pivot d' , so as to be capable of movement relative to the said member or lever c around the said pivot. It also is furnished 45 with an extension d^2 at one side of the pivot d' , such extension acting as a weight to over-balance the trip-arm and cause the latter to swing until the extremity of the said extension d^2 rests against the lever as in the drawings, 50 whereupon the said extension acts as a stop to limit the extent of such swinging movement. This is the normal position of the trip-arm relative to the lever c . The trip-arm d is notched for engagement with the 55 acting portion of the tappet or cam e . So long as the lever c and dog occupy their starting position, as shown, the trip-arm is supported with its notched portion entirely clear of the path described by the tappet or 60 cam in its movement. Consequently the lever and dog are unaffected by the movement of the tappet or cam, and no jiggling movement of the dog relative to the ratchet-teeth occurs. Hence wear of the contacting 65 portions of the dog and ratchet-teeth due

to unnecessary movements of the dog is avoided. When however the lever and dog are permitted to turn the feeder, the lever swings so as to place the notched end of the trip-arm in the position shown by dotted 70 lines in Fig. 1, wherein it is reached and engaged by the end of tappet or cam e in rotating. When the said portion of the said tappet or cam engages with the notched portion of the trip-arm in the rotation of the 75 tappet or cam, the latter acts through the said trip-arm to actuate the lever so as to retract the dog a as aforesaid, placing spring f under tension, the tappet or cam remaining in engagement with the trip-arm mean- 80 while, until, in consequence of the rotary movement of the tappet or cam, the trip-arm is swung upon its pivot d' far enough to bring the stop d^2 of the trip-arm against the top side of the lever c . The effect of this 85 is to hold the trip-arm d from turning farther around its pivot d' . Consequently, in the continued turning movement of the tappet or cam the latter becomes disengaged 90 from the trip-arm, leaving the lever c free to transmit the tension of the spring f to the feeder so as to hold the leading bobbin or other weft-carrier that is contained in the latter pressed against end-stop 18. As soon 95 as the trip-arm is released from the tappet or cam, it swings around its pivot d' into the position shown in full lines, out of the path of tappet or cam e , where it remains so long as the dog and the actuating member remain in their starting position. 100

The trip-arm arrangement is not in all cases restricted to use in connection with a continuously rotating tappet or cam.

The operation of the mechanism as thus far described is as follows: When the weft 105 replenishing mechanism is brought into action the transfferer 14, descends transffering the lowermost weft carrier held by the feeder into the shuttle. As the transfferer rises, the spring f , pulls down upon the rear 110 end of the power-transmitting lever c , thereby lifting the forward end of said lever and the dog a , thereby rotating the feeder through the ratchet 11, until the advance weft-carrier supported by the feeder comes 115 up against the stop 18. Also, as the rear end of the transmitting lever c , is pulled down by the spring, the lower end of the trip d , is brought to the position indicated by dotted lines in Fig. 1, where it is in the 120 path of the rotating cam e . As this cam rotates it encounters the trip thereby moving upwardly the rear end of the power transmitting lever c , restoring the tension to the spring f , and lowering the dog a , which 125 is pulled by the spring a' , into engagement with one of the ratchet teeth. The lever c , is directly connected to the dog a , and is distinct and separate from the transfferer. It constitutes power-transmitting means be- 130

tween the spring f , and the dog and is itself 5 acted upon by the cam so as to restore the dog back toward its starting position to take a fresh tooth of the ratchet thereby acting as power-transmitting means between the cam and the dog.

One means of manually controlling the feeder-actuating dog consists in a foot-treadle which is combined operatively with the lever c . In the embodiment of the invention that is shown in Fig. 1 a treadle g is thus combined with the said lever by being formed upon a branch c^4 of the latter. By pressing with one foot upon the treadle g 15 the weaver may operate the lever c to move the feeder-actuating dog to its starting position, where it may be held by a continuance of the pressure, or the foot-pressure may be relaxed to permit the spring f to 20 operate the lever c and dog to rotate the feeder. By depressing the lever far enough to relieve the pressure of the engaging end of the feeder-actuating dog against the face of the next tooth of the ratchet, forward 25 disengaging movement of the said engaging end away from the ratchet will be facilitated, and if at the same time that the weaver pulls such end forward the holding-dog or detent 12 also is moved out of engagement with the ratchet by taking hold of 30 its lug or handle 12^a , the feeder will be left quite free and capable of being turned in either direction until the treadle g and holding down dog or detent are released. Lever 35 c may be provided also with an extension g' adapted to be pressed against by the weaver's knee to operate the said lever in the same manner as has been explained with reference to treadle g , and for the same purposes. 40 The lever c may, if deemed advisable, be provided with a handle, projecting conveniently into position to be taken hold of by hand by the weaver, to manipulate lever c and dog a . By means of the treadle or other manual 45 controlling means, the lever and feeder-actuating dog may be held depressed so as to prevent the said dog from rising and falling, thereby rendering it more convenient and safe for the weaver to grasp the said 50 dog and the detent 12 and disengage them from the ratchet 11, as well as holding them disengaged, while he is occupied with filling vacant spaces in the feeder with reserve bobbins or other weft-carriers, and in turning 55 the feeder backward or forward for such purpose.

In the construction shown in Fig. 2 a separate treadle g^5 is employed, it being mounted pivotally at g^6 and normally held 60 in elevated position by a spring g^7 . This construction provides for disengaging the two dogs from the ratchet through connections with the treadle g^5 . In this construction, the actuating dog a^5 , mounted pivotally at a^6 upon the front arm of the le-

ver c , is furnished with a tail a^7 , projecting forward from the dog, from which tail a connecting wire a^8 extends to and through a collar g^8 carried by the treadle g^5 . A finger a^9 projects rearward from the hub-portion of the lever c in manner to engage with the under side of said lever so as to limit the forward swinging movement of the dog a^5 relative to the lever c . When the treadle g^5 is depressed, its collar g^8 slides 70 down along wire a^8 until it engages collar g^8 set-screwed upon such wire, and through engagement with such collar draws upon the wire a^8 , and by reason of the engagement of the said wire with the tail a^7 of the 75 dog a^5 acts to draw the lever and dog downward so as to relieve the pressure of the engaging end of the dog against the face of the tooth with which at the moment it is engaged, and also swing the dog forward 80 away from the ratchet until the stop-finger a^9 brings up against the underside of the lever c . In order to disengage the holding dog or detent 12 from the ratchet 11, at the same time, the said holding dog or detent 90 12 is furnished with a tail 12^a projecting forward from its pivot 13^a , and the said tail 12^a is joined by a connecting wire 12^b with the treadle g^5 . Consequently, by the depression of treadle g^5 , the feeder is rendered free 95 to be turned backward or forward by the weaver.

I claim as my invention:—

1. In weft-replenishing mechanism for looms, the combination with a stop, and a 100 feeder held from advancing movement through engagement of the leading weft-carrier with said stop, of a dog for operating the said feeder, a rotating loom-shaft, power-transmitting means directly connected with the dog and distinct from the transerrer, and means on the said shaft operating through the first mentioned means to move the dog back toward starting position to take a fresh tooth, and means for operating 105 the dog to advance the feeder when the said weft-carrier is transferred.

2. In weft-replenishing mechanism for looms, the combination with a stop, and a 110 feeder held from advancing movement through engagement of the leading weft-carrier with said stop, of a dog for operating the said feeder, a rotating loom-shaft, power transmitting means directly connected with the dog and distinct from the transerrer, and means on the said shaft operating through the first mentioned means to move the dog back toward starting position to take a fresh tooth, and means for actuating the feeder through the dog with 115 yielding force to advance the same when the said weft-carrier is transferred.

3. In weft-replenishing mechanism for looms, the combination with a stop, a feeder held from advancing movement through en- 120

- gagement of the leading weft-carrier with said stop, and its ratchet, of a dog which engages the said ratchet, a rotating loom shaft, power-transmitting means directly connected with the dog and distinct from the transerrer, and means on the said shaft operating through the first mentioned means to move the dog back toward starting position to take a fresh tooth, and means for 5 operating the dog with yielding force to advance the feeder when the said weft-carrier is transferred.
4. A weft-replenishing mechanism for looms having, in combination, a stop, a weft-carrier feeder held from advancing movement through engagement of the leading weft-carrier with said stop, its ratchet, a dog which engages said ratchet, a cam on a rotating loom-shaft, power-transmitting means distinct from the transerrer through 10 which said cam acts to move the said dog back to its starting position to take a fresh tooth, and a spring which actuates the said dog to rotate the feeder.
5. In weft-replenishing mechanism for looms, the combination with a feeder and its ratchet, of a dog which engages the said ratchet, a lever, distinct from the transerrer and its actuating connections, with 15 which the said dog is directly combined, said lever provided with means for yieldingly actuating the same and the dog to advance the feeder, and a cam on a rotating loom-shaft directly actuating the said lever to move the dog back toward starting position.
6. In weft-replenishing mechanism for looms, the combination with a feeder and its ratchet, of a dog which engages the said ratchet, a motion-transmitting member with 20 which the said dog is combined operatively, a moving tappet or cam, and a trip combined with the said member, adapted to be engaged by the cam in the advanced position of the dog to move the member and dog toward starting position, and to automatically release from and clear the cam when the dog is in starting position.
7. In weft-replenishing mechanism for 25 looms, the combination with a feeder and its ratchet, of a dog which engages the said ratchet, a motion-transmitting member with which the said dog is combined operatively, a cam on a rotating loom-shaft, and a trip combined with the said member, adapted to be engaged by the cam in the advanced position of the dog to move the member and dog toward starting position, and to automatically release from and clear the cam when the dog is in starting position.
8. In weft-replenishing mechanism for 30 looms, the combination with a feeder and its ratchet, of a dog which engages the said ratchet, a lever with which the said dog is connected, a moving tappet or cam, a trip

combined with the said lever, adapted to be engaged by the cam in the advanced position of the dog to move the lever and dog toward starting position, and to release automatically from the cam and clear the latter when 70 the dog is in starting position, said lever provided with means for yieldingly actuating the same and the dog to advance the magazine or feeder.

9. In weft-replenishing mechanism for 75 looms, the combination with a feeder and its ratchet, of a dog which engages the said ratchet, a lever with which the said dog is connected, a cam on a rotating loom-shaft, a trip combined with the said lever, adapted 80 to be engaged by the cam in the advanced position of the dog to move the lever and dog toward starting position, and to automatically release from and clear the cam when the dog is in starting position, said lever 85 provided with means for yieldingly actuating the same and the dog to advance the magazine or feeder.

10. In weft-replenishing mechanism for 90 looms, the combination with a feeder and its ratchet, of a dog which engages the said ratchet, an automatically operated actuating member for said dog, and means in connection with said actuating member for manually controlling the action of such member 95 and the dog.

11. In weft-replenishing mechanism for looms, the combination with a feeder and its ratchet, of a dog which engages the said ratchet, an automatically operated actuating 100 member for said dog, and means in connection with said actuating member for manually preventing actuation of the feeder by the dog.

12. In a weft-replenishing mechanism for 105 looms, the combination with a feeder and its ratchet, of a dog which engages the said ratchet, an automatically operated actuating member for said dog, and means in connection with said actuating member for manually relieving the pressure of the dog against the ratchet tooth engaged thereby and controlling the action of the actuating member and dog.

13. In a weft-replenishing mechanism for 115 looms, the combination with a feeder and its ratchet, of a dog which engages the said ratchet, an automatically operated actuating lever for said dog, and means in connection with said actuating lever for manually 120 controlling the action of the same and the dog.

14. In weft-replenishing mechanism for 125 looms, the combination with a feeder and its ratchet, of a dog which engages the said ratchet, an automatically operated lever combined with said dog and by its movements rendering the dog effective to move the magazine or feeder, and means for manually controlling the actuation of the 130

said lever and controlling the actuation of the feeder by the dog.

15. In weft-replenishing mechanism for looms, the combination with a weft-carrier feeder and its ratchet, of an automatically operated dog which engages the said ratchet and actuates the feeder to bring the weft-carriers successively to transferring position, and a lever operatively combined with the dog and by which the latter is manually controlled.

16. In weft-replenishing mechanism for looms, the combination with a weft-carrier feeder and its ratchet, of an automatically operated dog which engages the said ratchet to bring the weft carriers successively to transferring position, and a treadle operatively combined with the dog and by which the latter is manually controlled.

20 17. In weft-replenishing mechanism for looms, the combination with a weft-carrier feeder and its ratchet, of an automatically operated dog which engages said ratchet and actuates the feeder to bring the weft-carriers successively to transferring position, and a treadle by which the said dog may be actuated manually to advance the feeder.

25 18. In weft-replenishing mechanism for looms, the combination with a feeder and its ratchet, of a dog which engages the said ratchet and actuates the feeder, an automatically operated member combined with said dog and by its movements rendering the dog effective to move the feeder, and a treadle operatively combined with the said member and by which the actuation of the latter and in addition the actuation of the feeder by the dog are controlled.

30 19. In weft-replenishing mechanism for looms, the combination with a feeder and its ratchet, of a dog which engages the said ratchet and actuates the feeder, an automatically operated actuating lever for said dog, and means in connection with said actuating lever for manually relieving the pressure of the dog against the ratchet-tooth engaged thereby and controlling the action of the actuating member and dog.

35 20. In weft-replenishing mechanism for looms, the combination with a weft-carrier feeder, its ratchet, and a detent for said ratchet, of an automatically operated dog which engages the said ratchet and moves the feeder to bring the weft-carriers successively to transferring position, and a manually operable member, distinct from said detent, operatively combined with the said detent and dog and by which the detent may be disengaged from the ratchet and the dog manually controlled.

40 21. In a weft-replenishing mechanism for looms, the combination with a weft-carrier feeder, and its ratchet, and a detent for said

ratchet, of an automatically operated dog which engages the said ratchet and moves the feeder to bring the weft carriers successively to transferring position, and a treadle operatively combined with the said detent and dog and by means of which the detent may be disengaged from the ratchet and the dog manually controlled.

45 22. In weft-replenishing mechanism for looms, the combination with a feeder, and its ratchet, and a detent engaging with the said ratchet, of a dog which engages the said ratchet and actuates the feeder, an automatically operated member combined with said dog and by its movements rendering the dog effective to move the feeder, and a treadle operatively combined with the said member and with the said detent and by which the actuation of the said member and the actuation of the feeder by the dog are controlled and the engagement of the detent with the ratchet is controlled.

50 23. In weft-replenishing mechanism for looms, the combination with a feeder, and its ratchet, and a detent engaging with the said ratchet, of a dog which engages the said ratchet and actuates the feeder, an automatically operated member combined with said dog and by its movements rendering the dog effective to move the feeder, and a treadle operatively combined with the said dog and detent and by which the actuation of the feeder is controlled and the detent and dog are adapted to be disengaged from the ratchet.

55 24. In weft-replenishing mechanism for looms, the combination with a feeder, and its ratchet, and a detent engaging with the said ratchet, of an automatically operated dog which engages the said ratchet and actuates the feeder, and a treadle operatively combined with the said dog and detent and by which the actuation of the feeder is controlled manually and the detent and dog may be disengaged from the ratchet.

60 25. In weft-replenishing mechanism for looms, the combination with a feeder, its ratchet, and a detent engaging with the said ratchet, of an automatically operated dog which engages the said ratchet and actuates the feeder, and a manually operable lever, distinct from said detent, operatively combined with the said dog and detent and by which the actuation of the feeder is controlled manually and the detent and dog may be disengaged from the ratchet.

65 In testimony whereof I affix my signature in presence of two witnesses.

HENRY A. OWEN.
